UNITED STATES PATENT OFFICE

2,269,525

CARBON PAPER CONTAINER

Nathan Fleischer, Brooklyn, N. Y.

Application December 16, 1938, Serial No. 246,085

4 Claims. (Cl. 206—57)

This invention relates to improvements in containers for the packaging of carbon paper sheets.

The primary object of the invention resides in a carbon paper box in which individual sheets of carbon paper are arranged in stacked formation therein, may be removed therefrom without necessitating the reaching in and thumbing the sheets to facilitate individual grasping and withdrawal of the same, thus saving time for the typist and reducing the likelihood of the soiling of the fingers of the hand and wrinkling of the sheets during such withdrawal operation.

Another feature of the invention is to provide a carbon sheet paper box by which finger pressure applied to a predetermined portion of the cover thereof will cause the forward portion of the uppermost carbon sheet to be lifted from the pack of sheets, whereby an operator may by lifting of the cover reach into the box and conveniently remove a carbon sheet therefrom.

A further feature of the invention is the provision of a carbon sheet container having sheet pick-up means formed integral with the cover of the box, thus keeping the cost of manufacture of the box to a minimum.

Other features of the invention will be apparent as the specification is read in conjunction with the accompanying drawing, in which:

Figure 1 is a perspective view of a carbon sheet container constructed in accordance with one form of my invention, the box being illustrated in its normal closed position.

Figure 2 is a perspective view showing the carbon sheet container with the front cover section in raised position and with the pick up flap partially depressed.

Figure 3 is an enlarged vertical longitudinal sectional view on the line 3—3 of Figure 2, but showing a sheet of carbon paper being lifted for removal from the container.

Figures 4, 5, 6, and 7, are fragmentary top plan views of various modifications of the invention, a portion of Figure 6 being broken away.

Figure 8 is an enlarged vertical longitudinal sectional view on the line 8—8 of Figure 7.

Referring to the drawing by reference characters, and at present to the form of the invention shown in Figures 1 to 3 inclusive, the numeral 10 designates my improved carbon sheet container in its entirety which includes a rectangular tray like body 11 which comprises a flat bottom wall 12, and upstanding side walls 13. A pack of carbon paper sheets A snugly fit

into the tray body 11 with the carbon side of the sheet facing downwardly.

Fitting over the open top of the tray like body 11 is a cardboard cover 14 which includes a top wall 15 and downwardly extending side walls or flanges 16. The cover 14 telescopes the tray like body 11 with the depending flanges or side walls 16 of the cover snugly embracing the upstanding side walls 13 of the body. The cover 14 is divided 10 by a transverse fold line 17 into a rear cover section 18 and a front cover section 19, the longitudinal side walls 16 of the cover being cut as at 20 in line with the fold line 17 whereby the front cover section 19 may be swung upwardly and pivot on the fold line 17 while the rear cover section 18 remains in its normal position over the tray like body 11.

The front cover section 19 is provided with a U-shaped slit consisting of spaced longitudinal slits 21—21 and with a connecting transverse slit 22 to provide a depressible pick up flap 23. The flap 23 is arranged along the longitudinal center of the cover and the free edge of the flap 23 is disposed adjacent the front side wall 16 of the front cover section 19. In forming the slits 21 and 22, a break is provided in order to normally hold the flap 23 on the same plane as the top of the cover section 19, but which interruption in the slits does not interfere with the breaking of the flap 23 free so as to move inwardly of the cover as illustrated in Figures 2 and 3 of the drawing. The underside of the flap 23 adjacent the front free edge thereof is provided with a spot of adhesive substance 24 and which adhesive substance may be of the kind which remains tacky although exposed to the atmosphere.

Also cut from the front cover section 19 and disposed forwardly of the transverse slit 22 is a pull tab 25, which is formed by providing slits or weakened lines in the cover section 19 whereby normally the pull tab lies in the same plane as the top wall of the cover but which permits the pull tab 25 to be pulled upwardly as illustrated in Figure 3 of the drawing when the container is opened for use.

In practice, the container 10 with the pack of carbon sheets A packaged therein is received by the user in the form shown in Figure 1 of the drawing, and the typist in opening the container swings the front cover section 19 upwardly on the fold line 17 as illustrated in Figure 2, and proceeds to break the flap 23 inwardly and the pull tab 25 outwardly. The container is now pre-

pared for the individual removal of the carbon sheet A and when a sheet A is to be withdrawn from the container, the operator with the front cover section 19 in closed position places a finger on the pick up flap 23, and lightly presses upon the flap, causing the flap to move inwardly and contact the upper side of the uppermost carbon sheet A, whereupon the adhesion substance 24 causes the carbon sheet A to adhere to the flap 23, after which the operator grasps the pull tab 25 and swings the front cover section 19 upwardly, thus lifting the front end of the carbon sheet as best illustrated in Figure 3. It is now convenient for the operator to reach the front edge of the partially lifted carbon sheet and pull the same free of the adhesive substance 24 and withdraw the carbon sheet entirely from the tray like body 11. After each withdrawal of the sheet, the front cover section 19 is lowered to its closed position and the same procedure as above described takes place when the next uppermost sheet is to be withdrawn.

Whereas I have shown and described a cover divided into rear and front sections, I wish it to be understood that the cover may be of a single section, and the forward end lifted up with the rear end of the cover fulcruming on on the rear side wall of the body 11 without in any way departing from the spirit of the invention.

In Figure 4 of the drawing, I have illustrated a top plan view of a modified form of the invention, and in which the numeral 26 designates the cover of the container having a pick up flap 27 cut from the top wall thereof and which is identical with the flap 23 with the exception that the free end of the flap faces rearwardly instead of forwardly. The underside of the flap 23 is provided with a spot of adhesive 28 and a lifting pull tab 29 is cut from the flap 27.

In Figure 5 of the drawing, the numeral 30 designates the cover which telescopically fits the tray like body 11 and which cover has slit or weakened lines 31 at the front and forward sides of the cover to permit of the breaking out of a front cover section 32 which may pivot on the transverse fold line 33. A finger slot 34 is provided along the front weakened line 31 to enable the finger of an operator to reach the front edge of the cover section 32 in order to tear the same on the weakened lines 31. With the front cover section 32 torn free and pivoting on the fold line 33, the entire section 32 may drop into the body 11 and rest upon the uppermost of the carbon sheets. The pivoted cover section 32 is provided with a spot of adhesive 35 adjacent its front edge and pressure applied to the top of the section 32 adjacent the front edge will cause the adhesive substance 35 to adhere to the uppermost carbon sheet. The front section 32 rearward of the spot of adhesive 35 is provided with a finger grip tab 36 which permits of the lifting of the cover section 32 after the uppermost carbon sheet becomes adhered to the adhesive spot 35.

In Figure 6 there is shown a further modified form wherein the cover 37 is scored transversely on the dotted line 38 to provide a front pivoted cover section 39. Cut from and disposed adjacent the front edge of the section 39 is a finger tab 40 by which the section may be swung upwardly. The cover section 39 rearward of the tab 40 is provided with an opening 41 and disposed beneath the opening 41 is the free end 75

or the like, the rear end of the tongue being fixed to the underside of the box by a staple 43. The free front end of the tongue 42 has a spot of adhesive 44 on the under side thereof. In practice, the operator inserts a finger through the opening 41 and depresses the front end of the tongue 42 so as to cause the adhesive spot 44 to contact the uppermost carbon sheet, whereupon lifting of the cover section 39 by grasping the tab 40 will effect a lifting of the front end of the carbon sheet so that an operator may grasp the lifted portion of the carbon sheet and remove the same from the container.

In Figures 7 and 8 of the drawing, there is shown a still further modified form in which the numeral 45 designates the top cover of the container and which is formed with a transverse fold line 46 for dividing the cover into a hinged front cover section 47 and a rear cover section 48. Secured to the underside of the front cover section 47 by a metal staple 49 is a resilient spring tongue 50, the front free end of which is provided with a spot of adhesive 51 on the underside thereof. The tension of the tongue 50 causes the adhesive spot 51 to always contact the uppermost of the carbon sheet, thus eliminating the necessity of applying pressure to cause the pick up element to engage with the sheet to be removed. To facilitate lifting of the front cover section 47, the forward portion of the top thereof is provided with a punched out finger grip tab 52.

From the foregoing description, it will be seen that I have provided a carbon paper box in which the front portion of the uppermost sheet of a stack of carbon sheets may be picked up with the opening of the cover of the container, whereby a typist may conveniently reach in and grasp the lifted portion of the carbon sheet and withdraw the same from the container.

While I have shown and described what I consider to be the most practical embodiment of my invention, I wish it to be understood that other changes and modifications may be resorted to as come within the scope of the appended claims.

Having thus described the invention, what I claim as new and desire to secure by Letters Patent of the United States, is:

1. A container for loose paper sheets comprising a box body adapted to contain a pack of paper sheets, a relatively stiff cardboard cover fitting over said body, a depressible hinge flap struck out from said cover, and an adhesive substance provided on the underside of said hinge flap whereby manual downward swinging movement of said flap will cause said adhesive substance to contact the uppermost sheet of a pack of sheets for separation therefrom upon subsequent upward tilting of said cover.

2. A container for loose carbon paper sheets comprising a tray-like body adapted to contain a pack of carbon paper sheets, a relatively stiff cardboard cover fitting over said body, a depressible hinge flap struck out from the top wall of said cover adjacent the front end thereof, a spot of adhesive provided on the underside of said hinge flap whereby manual downward pressure applied to said hinge flap will cause the adhesive thereon to engage the uppermost sheet of a pack of carbon paper sheets and subsequent lifting of the front end of said cover will cause the front portion of an uppermost carbon sheet to be lifted therewith for easy withdrawal from the tray-like body.

3. A container for loose carbon paper sheets comprising a tray-like body adapted to contain a pack of carbon paper sheets, a relatively stiff cardboard telescoping cover fitting over said body, a substantially U-shaped slit provided in the top wall of said cover adjacent the front edge thereof and defining a depressible hinge flap, and a non-drying adhesive provided on the underside of said hinge flap, whereby a user may manually press downward upon the hinge flap and cause the same to swing inwardly into the tray-like

body to cause the adhesive to forcibly contact the uppermost of a pack of carbon paper sheets thereby causing the sheet to adhere thereto for subsequent removal therefrom upon the upward tilting of the front end of said cover.

4. A container for loose carbon paper sheets as set forth in claim 3, including a pull tab formed from the top wall of the cover by weakening or slitting the top wall on two spaced lines 10 extending from the U-shaped slit.

NATHAN FLEISCHER.
